UNITED STATES PATENT OFFICE

1,925,329

ATOMIZING OIL BURNER HEAD

Herbert V. Leahy, Los Angeles, Calif.

Original application March 16, 1929, Serial No. 347,524, now Patent 1,874,017, August 30, 1932. Divided and this application May 7, 1930. Serial No. 450,541

13 Claims. (Cl. 299—140)

This invention relates to oil burner heads and of the external and semi-internal atomizing type, and a very important object of the invention is to prevent cracking of the oil within the burner head, thereby insuring against clogging of the passages in the burner head by hardened carbon which, as is well known, is difficult to remove.

Another important object is to provide a construction whereby adjustment of the burner head may be made to direct the flame at various angles without the necessity of changing the position of the piping and without the necessity of bending the pipes that lead to the burner head.

Another very important object is to effect cooling of the burner head by the atomizing fluid, thus eliminating one of the greatest faults found with other burners of this type, namely, carbonization and cracking of some of the burner parts. Carbonization of other burners of this type is caused by the intense heat that is reflected onto them by the walls of the combustion chamber or fire box with which the burners function.

Another important object is the production of a burner head of this type of comparatively simple construction and one in which the various parts can be readily replaced at a comparatively small cost.

Another object is to effect a change in the extent of the spread of the flame, to suit the various conditions under which the burner head may be operating, by removal of but one part of the burner head and the substitution therefor of a similar part.

Another important object is to make provision for use of the burner head for both horizontal and vertical firing, and to obtain the same advantages in either case. This is quite important in the securing of low manufacturing costs.

Another very important object is to make provision for feed of the fuel upon the atomizing agent in an arc at a right angle to the direction of flow of the atomizing agent.

Another important object is to make provision for feeding of a predetermined amount of the atomizing agent to the oil slightly in advance of the impingement of the oil against the main stream of the atomizing agent, thus aiding in atomization of the oil into exceedingly fine particles.

Another important object is to provide a construction that will facilitate the employment of deflecting elements of various shapes and the

substitution of one for the other. By employing these deflecting elements in conjunction with the construction whereby a given amount of auxiliary atomizing agent is injected into the oil, as mentioned above, the deflecting elements function to additionally mix the oil and atomizing agent externally of the burner head, thus causing the burner head to function as a semi-internal or inter-mixture atomizing type.

Another important object is to provide a construction that will facilitate the use of either a flat-faced or a bevel-faced ring, extending laterally beyond the oil feed port so as to secure a burner head of the semi-internal or inter-mixture atomizing type having the additional advantage of effecting projection of the atomizing mixture, by reason of the bevel-faced ring, downwardly at the angle of bevel of said ring.

Other objects and advantages will appear in the subjoined detailed description:

The accompanying drawing illustrates the invention:

Figure 1 is a plan view of a burner head constructed in accordance with the provisions of this invention.

Figure 2 is an enlarged vertical section on the irregular line indicated by 2—2, Fig. 1.

Fig. 3 is an enlarged fragmental vertical section on the line indicated by 3—3, Fig. 1.

Fig. 4 is a fragmental horizontal section on the line indicated by 4—4, Fig. 3.

Fig. 5 is a horizontal section on the line indicated by 5—5, Fig. 3.

Fig. 6 is an enlarged vertical section on the line indicated by 6—6, Fig. 1.

Fig. 7 is a sectional view similar to Fig. 3, showing a slightly modified form of the invention.

Fig. 8 is a horizontal section on the line indicated by 8—8, Fig. 7.

Fig. 9 is a sectional view similar to Fig. 3, illustrating a still different form of the invention.

Fig. 10 is a sectional view similar to Fig. 2, illustrating a slight modification in the construction of one of the burner head sections.

First, referring to Figures 1 to 6 of the drawing, a burner head is indicated, in general, by the character A, and is connected by oil and atomizing agent tubes 11, 12, respectively, to suitable sources of supply of fuel oil and atomizing agent, such as air or steam. The tubes 11, 12, for example, may be connected to a suitable by-pass of the type disclosed in my copending application Serial Number 347,524, filed March 16, 1929, of which this application is a division and

upon which Patent Number 1,874,017 was issued on August 30, 1932.

The body of the burner head may be constructed in one piece, if desired, but in the present instance, said body, preferably, is of sectional construction, there being a forward section 13 and a rear section 14. The section 13 is swivelled on the section 14 by a bolt 261, thus enabling the section 13 to be turned to angular positions with respect to the tubes 11, 12 which support the burner head. Shoulders 16 on the section 14 limit angular movement of the section 13.

The section 14 is provided with separate passages 17, 18 which extend lengthwise therein. The passage 17 receives oil through a threaded opening 19 into which is screwed one end of the tube 11, and the passage 18 receives the atomizing agent through a threaded opening 20 into which is screwed the tube 12. It is to be particularly noted that the atomizing agent passage 18 extends along the upper side of the head section 14 and that the oil passage 17 extends along the lower side of said section or, in other words, beneath the passage 18, thus materially shielding the oil against heat that may be reflected from the furnace onto the top of the head section 14. Also, it will be noted that the oil tube 11 lies within the atomizing agent tube 12 so that the atomizing agent protects the tube 11 from the heat radiated by the furnace.

The sections 13, 14, I provide with flat contacting faces 21, 22, respectively, and opening through the flat faces 21 are ports 23, 24. Also opening through the flat faces 22 are ports 25, 26 which are, respectively, aligned at all times with the ports 23, 24, all of said ports being elongate so as to pass the atomizing fluid and the oil regardless of the angle at which the section 13 may be positioned with respect to the section 14.

The head section 13 is provided with lower and upper passages 27, 28, that communicate with the ports 23, 24 so that, in this case also, the atomizing fluid passage 28 is above the oil passage 27, thereby entailing that the oil passage is shielded by the atomizing fluid from heat reflected on the upper side of the head section 13 from the furnace walls.

In this instance, the faces 21, 22 are held in close contact by the bolt 261 which passes through solid hub portions 262, 263 of the head sections 13, 14, respectively, the hub portion 262 separating the port 23 from the port 24 and the passage 27 from the passage 28; and the hub portion 263 separating the port 25 from the port 26 and the passage 17 from the passage 18. The port 25 communicates with the passage 17 and the port 26 communicates with the passage 18.

The passage 28 terminates at its forward end in a circular bore portion 29 and said bore portion 29 terminates downwardly in an annular shoulder 30 against which seats a chambered cylindrical member 31 which is provided with a threaded stud 32 that projects upwardly through the bore portion 29 and through an opening 33 in the top of the head section 13. On the outer end of the stud 32 is threaded a nut 34 whereby the member 31 is pulled tight against the seat 30.

The member 31 is provided with a transversely extending passage 35 which communicates at its rear end with the passage 27 so as to form, in effect, a continuation of said passage 27. The forward end of the passage 35 communicates with a transversely extending segmental slot 36

which, in turn, communicates at its forward end with an arcuate vertical oil discharging slot 37 that is formed in the outer face of a bushing 38 that surrounds a portion 39 of the member 31, said portion 39 being of a reduced diameter. In other words, the upper end portion of the member 31 is provided with an external cylindrical flange 40 which fits a bore portion 41 of the head section 13, whereas the reduced portion 39 leaves an annular recess in which is disposed the bushing 38.

The bushing 38 is spaced somewhat from the flange 40 and said bushing is provided with an external flange 42, which seats against a lower face 43 of the head section 13. Projecting downwardly from the member 31, axially thereof, is a threaded stud 44 on which is screwed a nut 45 that bears against the under face of a ring 46 that is held against the lower end of the bushing 38 which projects some distance below the face 43. The ring 46 surrounds a reduced portion 47 of the nut 45. The lower end of the bushing 38 has a portion cut away to define an arcuate slot 48 lying between said bushing 38 and the ring 46, the atomizing fluid being adapted to discharge horizontally through said slot 48 so that the oil discharging through the arcuate slot 37 will impinge on the stream of atomizing fluid as said atomizing fluid issues from the slot 48. The upper face of the ring 46 is recessed at 481 so as to form, in conjunction with the bore of the bushing 38, an expansion chamber for the atomizing fluid. The bore of the bushing 38 communicates with the chamber 29 through a vertical port or ports 49 in the member 31 said ports 49 passing on opposite sides of the passage 35 and being separated therefrom, as is clearly shown in Fig. 4. Thus, the atomizing fluid as it passes downwardly through the ports 49 protects the oil in the passage 35 from heat reflected from the furnace onto the sides of the head section 13.

In order that the member 31, and bushing 38 may be easily assembled in proper position in the head section 13, I provide a pin 491 in the member 31, said pin projecting laterally from said bushing through a vertical slot 492 in the bushing 38 and into a vertical slot 493 in the head section 13, the slot 492 opening to the bottom edge of the bushing and the slot 493 opening to the face 43 so that, in assembling, the member 31 and bushing 38 will first be telescoped and then the bushing, with the member 31 therein, will be slid into the bore that is to receive it.

The form of the invention illustrated in Figs. 7 and 8 is very little different from the construction hereinbefore described and the parts that are the functional equivalents of those above described are indicated by the same reference characters with the addition of the suffix *a*. In this form of the invention the vertical arcuate slot 37a communicates with the slot 38a, not only, but it is extended upwardly past the flange 40a of the member 31a so as, also, to communicate with an arcuate opening 50 that is cut through said flange, thereby permitting a predetermined amount of atomizing fluid to discharge from the bore portion 29a past the flange 40a into the upper end of the slot 37a. Because of the atomizing fluid discharging under higher pressure than the oil, it follows that, in this form of the invention the oil will be discharged from the slot 37a under a pressure substantially equal to the pressure of the atomizing fluid discharging from the slot 48a.

Consequently, the resulting mixture produced

at the circular line of impingement of the vertically and horizontally directed streams will be directed aslant downwardly and forwardly from the burner, and this angle of discharge of the mixture will be governed more or less by the ring 46a which extends horizontally beyond the periphery of the bushing 38a. Thus the ring 46a is of larger outside diameter than the ring 46 hereinbefore described. In this instance, the ring 46a is provided with a downwardly and outwardly beveled upper face 51, it being understood that rings with faces of varying degrees of bevel may be associated with the head section 13 so as to thereby control, at least to some extent, the downward deflection of the combustible mixture.

The form of the invention illustrated in Fig. 9 follows very closely the construction illustrated in Figs. 7 and 8 and the elements that function the same are indicated by the same numeral portions of the reference characters with the addition of the suffix *b*. The only difference is that the ring 46b has that portion of its upper face 51b, that extends beyond the periphery of the bushing 38b, substantially horizontal, thus preventing any material downward deflection of the combustible mixture produced by the burner.

Now referring, more particularly, to Fig. 10, the parts that functionally correspond to those illustrated in Fig. 2 are indicated by the same reference characters with the addition of the suffix *a*. Instead of the tube 11a being inside of the tube 12a, as in Fig. 2, said tubes are eccentrically related and the passages 17a, 18a within the section 14a are modified, accordingly. It may be readily seen that any of the burner head sections 13, 13a, 13b may be used with the burner head section 14a, just described.

The foregoing will make clear the construction and operation of the invention and, briefly, stated, the operation is as follows: The bushings 38, 38a or 38b, and the rings 46, 46a, or 46b having been installed, and the head section 13 having been suitably adjusted to the desired angle relative to section 14, the valves, not shown, that control the flow of atomized fluid and oil to the tubes 11, 12, will be opened to admit said fluid and oil to the various passages hereinbefore described. In the event of the assembly being that illustrated in Fig. 3, the oil will discharge from the slot 37 under a relatively low pressure and impinge on the atomizing stream issuing from the slot 48, thereby producing a finely atomized combustible mixture that is ignited and burned in a manner well understood in this art.

In the event that the assembly is that of Figure 7, a predetermined quantity of the atomizing fluid will mix to some extent with the oil in the slot 37a and the oil and steam (or air), will discharge from the slot 37a at the relatively high pressure of said steam (or air).

The downwardly directed oil and atomizing fluid from the slot 37a will impinge upon the high pressure atomizing stream issuing from the slot 48a, thus further mixing the atomizing fluid and the oil and atomizing the oil, and the mingled streams of atomizing fluid and oil impinge upon the ring 46a, thereby still further atomizing the mixture.

In the event of the assembly being that of Figure 9, the same results are secured as described above in connection with Figure 7, excepting that the mixture will be discharged from the burner at a right angle to the axis of the bushing 38b.

Special attention is directed to the construction hereinbefore described whereby the bushing 31 is held tightly against the head section 13, thus making it impossible for air or steam to leak around the ring and come in contact with the oil within the burner head.

Also, to be particularly noted, is the construction of the passage for the atomizing fluid at the top, the passage for the oil at the bottom, the ports at the side connecting these passages, and the oil passage located between the upper and lower passages, on the one hand, and between the ports 49, on the other hand, thereby surrounding the oil, at that portion of the burner that is exposed to the highest temperature, with steam or air so that said oil will not be at a higher temperature than the steam or air and, accordingly, not subjected to cracking temperatures that would tend to cause a deposition of hard carbon within that portion of the burner, thus making it difficult to clean.

Another point to be observed is that, because of the particular construction of the head section 13, member 31, bushing 38, and the studs 32, 44 and nuts 34, 45 for separately holding the member 31 and bushing 38 assembled with the head section 13, access may be had to the lower chamber for the atomizing fluid without disturbing the upper chamber for said fluid, and, also, access may be had to the upper chamber without disturbing the lower chamber.

Because of the construction, illustrated in Figs. 7 and 8, providing for the atomizing fluid passing from the upper chamber through ports into the lower chamber and through the passage 50 in the flange 40a, thence into the upper portion of the slot 37a, all parts of the burner head are maintained at a temperature approximately that of the atomizing agent.

I claim:

1. An atomizing oil burner comprising a head provided with oil and atomizing fluid passages and provided with a bore connecting said passages, a member positioned in and sealing said bore and provided with a passage communicating with one of the passages in the head, said member being provided with a port communicating with the bore, an annular bushing surrounding said member and having a portion of its exterior wall cut away to form an arcuate discharge slot between the bushing and the wall of the bore communicating with the passage in said member, a ring fitting against the end of said bushing having a portion spaced from the bushing to form a slot communicating with said port, and means to hold said ring toward said bushing.

2. An atomizing oil burner comprising a head having a vertical bore, an oil passage leading into the side of said bore, a member positioned in and sealing said bore and juxtaposed to said passage, a transverse passage in said member connecting with said passage, a bushing concentrically positioned between the wall of said bore and said member, a portion of the circumference of said bushing being cut away to form with the wall of said bore a downwardly directed arcuate oil discharge slot therebetween both lateral dimensions of which may be varied by varying the depth and width of the cut away portion of the bushing, passages through said bushing juxtaposed to the transverse passage in said member, one of said latter passages communicating with said arcuate discharge slot, means accessible from the exterior of said head for detachably securing said bushing to said member, said head having a passage for

- supplying atomizing fluid to the upper end of said bore above said member, means defining an atomizing fluid discharge orifice adjacent the lower end of said head for discharging atomizing fluid 5 into the oil stream discharged from said arcuate discharge slot, said member having a passage extending vertically therethrough for connecting the upper end of said bore with said atomizing fluid discharge orifice.
- 10 3. An atomizing oil burner comprising a head having a vertical bore, an oil passage leading into the side of said bore, a member positioned in and sealing said bore and juxtaposed to said passage, a transverse passage in said member connecting with said passage, a slot in said member communicating with said transverse passage therein, a bushing concentrically positioned between the wall of said bore and said member, a portion of the circumference of said bushing being cut away 20 to form with the wall of said bore a downwardly directed arcuate oil discharge slot therebetween both lateral dimensions of which may be varied by varying the depth and width of the cut away portion of the bushing, passages through said bushing juxtaposed to the transverse passage in said member, one of said passages opening into the slot in said member, said passage also communicating with said arcuate discharge slot in said bushing, means detachably securing said bushing to said member, said head having a passage for supplying atomizing fluid to the upper end of said bore above said member, means defining an atomizing fluid discharge orifice adjacent the lower end of said head for discharging atomizing fluid into the oil stream discharged from said arcuate discharge slot, said member having a passage extending vertically therethrough for connecting the upper end of said bore with said atomizing fluid discharge orifice.
- 30 4. An atomizing oil burner comprising a head having a vertical bore, an oil passage leading into the side of said bore, a member positioned in and sealing said bore and juxtaposed to said passage, a transverse passage in said member connecting with said passage, a bushing concentrically positioned between the wall of said bore and said member, a portion of the circumference of said bushing being cut away to form with the wall of said bore an arcuate discharge slot therebetween, passages through said bushing juxtaposed to the transverse passage in said member, one of said passages communicating with said arcuate discharge slot, an atomizing fluid discharge slot in said bushing below said arcuate oil discharge slot whereby fluid is 35 issuing from the atomizing fluid discharge slot impinges on the oil stream issuing from said arcuate discharge slot, and means detachably securing said bushing to said member.
- 40 7. An atomizing oil burner, as described in claim 6, further characterized in that said member contains two vertical ports communicating with said bore, said ports being positioned respectively on either side of said transverse passage.
- 45 8. An atomizing oil burner, as described in claim 1, characterized in that said means for holding said ring towards said bushing comprises a stud extending downward from said member and a nut screwed on said stud exterior of said ring.
- 50 9. An atomizing oil burner comprising a head having a vertical bore, an upper atomizing fluid passage in said head leading into the side of said bore, a lower oil passage in said head leading into the side of said bore, a member positioned in and sealing said bore containing a transverse passage juxtaposed to said oil passages in said head, a horizontal slot in said member connecting with said passage, a bushing concentrically positioned between the wall of said bore and said member, a portion of the circumference of said bushing extending below the horizontal slot in said member being cut away to form with the wall of said bore an arcuate vertical discharge slot therebetween, 55 vertical ports in said member communicating with said bore, a ring juxtaposed to the end of said bushing, a portion of the lower edge of said bushing being cut away to form a horizontal slot between the bushing and said ring, the outer edge of said ring being flush with the outer face of said bushing, and means for holding said ring against said bushing.
- 60 10. An atomizing oil burner, as described in claim 9, except that said ring extends radially 65

out beyond the outer circumference of said bushing and has a beveled upper edge.

11. An atomizing oil burner, as described in claim 9, except that said ring extends radially beyond the outer circumference of said bushing, and has a substantially horizontal upper face.

12. An atomizing oil burner comprising a head having a vertical bore, an upper atomizing fluid passage in said head entering the upper portion of said bore, a lower oil passage in said head entering said bore, a member positioned in and sealing said bore between the points of entry of said upper and lower passages and sealing about the point of entry of said lower oil passage, an atomizing fluid chamber being provided between the upper part of said member and the top of the bore, a transverse oil passage in said member juxtaposed to and connected with said lower passage in said head, a bushing concentrically positioned between said member and the wall of said bore, a portion of the outer wall of said bushing being cut away to form an arcuate discharge passage connected with said transverse passage, and a portion of the top of said member being cut away to provide a passage between the atomizing fluid chamber above said member and said arcuate discharge passage, a ring secured against the lower end of said bushing forming a lower chamber therebetween, ports in said member connecting said upper and lower chambers, a portion of the bushing adjacent said ring being

cut away to form an atomizing fluid discharge passage between said bushing and ring.

13. An atomizing oil burner comprising a head having a vertical bore therein, an inwardly extending shoulder at the upper end of said bore, an outwardly extending shoulder at the lower end of said bore, a passage leading into the side of said bore, a member positioned in said bore juxtaposed to said passage having a shoulder sealing with said inwardly extending shoulder, said member containing a transverse passage connecting with said first passage, a bushing concentrically positioned between the wall of said bore and said member, a portion of the outer wall of said bushing being cut away to form with the wall of said bore an arcuate discharge slot therebetween, passages through said bushing juxtaposed to the transverse passage in said member and communicating therewith, one of said passages also communicating with said arcuate discharge slot, an outwardly extending shoulder on said bushing sealing with the outwardly extending shoulder at the lower end of said bore, means for securing said member to said head with its shoulder in compression against said inwardly extending shoulder, and independent means for securing said bushing to said member with its outwardly extending shoulder in compression against the shoulder at the lower end of said bore.
